UNITED STATES PATENT OFFICE.

ANDREW YOST, OF STEELTON, PENNSYLVANIA.

TRUSS.

SPECIFICATION forming part of Letters Patent No. 503,223, dated August 15, 1893.

Application filed January 19, 1893. Serial No. 458,925. (No model.)

To all whom it may concern:

Be it known that I, ANDREW YOST, of Steelton, county of Dauphin, and State of Pennsylvania, have invented certain new and useful Improvements in Trusses, of which the following is a specification, reference being had to the accompanying drawings.

The object of my invention is to produce an improved truss which will give greater comfort to the wearer and greater ease of movement without danger of displacement than may be had with those in ordinary use.

In the accompanying drawings, Figure 1 is a front view of my truss; Fig. 2 a top plan view thereof. Fig. 3 is a view of one of the springs, detached; and Fig. 4 a similar view of a modified form thereof.

Referring to the figures on the drawings, 1 indicates a belt of suitable flexible material, as for example leather. It is provided with loops 2 on one or both sides, depending upon whether the truss is to be used for single or double hernia.

3 indicates eyelets in one end of the strap. 25 4 indicates a bent spring having in one end a ring which enters one of the loops 2, and which affords a broad bearing upon the back of a wearer for the spring. At its other end it is provided with a longitudinal slot 5, which 30 is adapted to movably carry a pad 6 which is provided with a flanged button 7 for holding it in place, and admitting of its moving freely in any direction in the slot.

8 indicates a supporting pad designed to 35 assist the pad 6 in performing its office of sustaining single hernia.

9 indicates a catch upon the end of the spring which is inserted into one of the eyelets 3, and is adapted, when the strap encircles the waist, to hold the truss securely in 40 place. The spring is preferably secured to the strap altogether by the loops 2. If the strap is made of very light leather it is preferably provided with stiffening plates 10 at intervals to prevent the leather from biting 45 into the flesh of the wearer.

The spring may be made of round wire, as illustrated in Fig. 3, or of flat spring metal, as illustrated in Fig. 4.

In applying my truss the spring or springs, 50 as the case may be, are set in place, the rings in their ends serving to afford a broad firm bearing for them. The slotted end of the spring is then brought opposite the hernia and the pad is properly adjusted. The spring 55 is then fastened in place. By the use of my strap a great freedom of movement is permitted and danger of displacement avoided.

What I claim is—

In a truss the combination with a belt provided with loops, of a superimposed spring provided at one end with a ring adapted to be passed through one of the loops and at the other with a slot, and a pad adjustably secured within the slot, substantially as specified.

In testimony of all which I have hereunto subscribed my name.

ANDREW YOST.
